UNITED STATES PATENT OFFICE.

ANDREW N. BAADE, OF SPOKANE, WASHINGTON.

ROTARY PUMP.

1,112,515.

Specification of Letters Patent.

Patented Oct. 6, 1914.

Application filed January 25, 1913. Serial No. 744,187.

To all whom it may concern:

Be it known that I, ANDREW N. BAADE, a citizen of the United States, residing at Spokane, in the county of Spokane and State of Washington, have invented certain new and useful Improvements in Rotary Pumps, of which the following is a specification.

This invention relates to rotary pumps, and has special reference to pumps intended for irrigating purposes and which are suspended within a deep well so as to rotate about a vertical axis.

One object of my present invention is to provide a pump in which the parts will be so constructed and arranged that the rotating piston will be relieved of weight so that it will not unduly wear upon the casing or its supports.

A further object of the invention is to provide an efficient system of lubrication whereby the piston and the parts working therein will be thoroughly lubricated so that the pump may be operated easily and at a high speed without an excessive expenditure of power.

A further object of the invention is to provide means whereby the pump will be supported concentrically within the well and out of contact with the sides of the same so that wear upon the pump cylinder from vibration and contact with the well casing will be avoided.

A still further object of the invention is to provide means for supporting the pump whereby it may be readily adjusted within the well and the operating parts will be relieved of all supporting strain so that the friction between moving parts will be minimized.

The invention also has for its object the provision of a pump that may be lowered into a small drilled well, thereby avoiding the expense of digging a large well; and an additional object of the invention is to avoid the necessity of entering the well to start or stop the pump.

A still further object of the invention is to provide novel means for projecting and retracting the blades by which the water is drawn into and expelled from the pump cylinder, and, finally, the invention seeks to improve, generally, the construction and arrangement of a vertically disposed rotary pump to the end that the efficiency and durability of the same may be increased.

The several stated objects, and such other

objects as will incidentally appear from the following description, are attained in such an apparatus as is illustrated in the accompanying drawings, and the invention consists in certain novel features which will be particularly pointed out in the claims following the description.

In the drawings.—Figure 1 is an elevation of my improved pump with a part broken away and in section; Fig. 2 is an enlarged vertical section through the pump cylinder and the piston mounted therein; Fig. 3 is a horizontal section taken on the line 3—3 of Fig. 2; Fig. 4 is a horizontal section taken on the line 4—4 of Fig. 2; Fig. 5 is a detail horizontal section taken on the line 5—5 of Fig. 2; Fig. 6 is a perspective view of the eccentric shaft, the blades, and the supports for the blades, the parts being shown free of the piston and with some of the retaining rings and ring segments separated but in their proper relative positions; Fig. 7 is a detail plan view of the upper retaining head with the shaft therein shown in section on the line 7—7 of Fig. 2; Fig. 8 is a similar view taken on the line 8—8 of Fig. 2; Fig. 9 is an enlarged detail vertical section of the support for the upper end of the driving shaft.

In carrying out my present invention, I employ a supporting frame consisting of sills 1 which are placed upon the surface of the ground adjacent the mouth of the well, and rising from the said sills are posts or standards 2 having beams 3 secured to and extending across their upper ends. A plate 4 is secured upon the beams 3 and through the said plate and the beams is formed an opening or openings 5 which are of considerably greater diameter than the driving shaft, so that, if the driving shaft support should be disposed at an angle or inclination, the shaft will not be caused to wear against the sides of the openings. Above the base plate 4 is disposed a supporting plate 5' through which bolts or studs 6 are threaded, the lower ends of said bolts or studs engaging sockets or recesses in the upper side of the base plate 4, so that, by rotating the studs or bolts, the supporting plate 5' may be raised or lowered. In the upper face of the plate 5' is formed a race-way 7 to receive balls or other anti-friction devices 8, and a second ring or plate 9 having a race-way in its under surface is fitted to the said balls so as to move freely thereon.

Through the said plates 5' and 9 openings 10 are formed in alinement with the openings 5 through the beams 3 and the base plate 4. In the upper face of the upper plate 9 at the center of the same is a concaved recess 11 in which fits a collar or block 12 having a convex lower end and firmly secured to the upper end of the driving shaft section 13. The section 13 of the driving shaft is solid and extends downward through the several openings 10 and 5 to a coupling or union 14 by which it is firmly connected to the upper end of the hollow driving shaft section 15, a pulley 16 being fitted securely 10 upon the said shaft section 13 below the beams 3 and connected by a power belt 17 with any convenient or preferred form of motor. A packing box, indicated at 18, is fitted around the shaft section 13 above the 15 coupling 14 and this packing box is carried by the upper end of a T-coupling 19 by which the discharge pipe 20 is connected with the conductor or tubular casing 21 rising from the pump cylinder. The tubular 20 casing or conductor 21 is composed of a series of sections which may be more or less according to the depth of the well, and the meeting ends of the sections are connected by collars 22 threaded onto the same, as 25 will be readily understood. A curb or other support 23 is secured to the sills 1 and the conductor 21 is connected with the said curb so as to remain stationary. The lower extremity of the conductor or tubular casing 21 is 30 threaded into the upper end of a reducing cap 24 which is rigidly secured to the upper end of a cylinder or casing 25 by long bolts or screws 26 inserted through an annular flange or shoulder 27 of the cap and entering 35 the wall of the cylinder, as shown in Fig. 2 and as will be readily understood. The lower end of the reducing cap 24, which is also the lower edge of the shoulder or flange 27 of the same, does not rest directly 40 upon the upper end of the cylinder 25, but a head 28 is interposed between the cap and the cylinder and secured rigidly in place by the bolts 26, as clearly shown in Fig. 2. This head 28 extends entirely across the upper end of the cylinder 25 so as to form a 45 closure for the same and it is provided adjacent its edge with a segmental slot 29 which constitutes an outlet for the water, the innermost wall of the said slot being beveled or inclined, as shown at 30, so as 50 to facilitate the flow of the water into the cap 24 and toward the tubular conductor 21 by which the water is conveyed to the discharge pipe 20. The hollow member 15 of 55 the driving shaft is provided with a plurality of perforations or openings 31 at its upper and lower ends so that the water may rise through the said shaft section as well as through the conductor 21 and, consequently, the friction of the water against 60

the conductor will be less pronounced than if it were confined solely in the space between the driving shaft and the conductor. The water will thus flow more rapidly and less power will be required to drive the 70 pump. The lower end of the driving shaft section 15 is secured by a collar or union 32 to the upper angular end 33 of a short shaft 34 which is journaled in the head 28 and a hub 35 formed thereon and has its lower 75 end 36 projecting below the head and secured by brazing, welding, or any other well-known metal-working process to the cap or head 37 of the piston. This short shaft 34 is provided with a small axial passage, indicated in dotted lines at 38, through which lubricant may pass to escape between the shaft and the bushing 39 around the same within the hub 35, so that the rotation of the shaft within the said hub and the 80 head 28 will be facilitated and the wear between these parts minimized.

In the lower extremity of the shaft 34 is a small socket which is engaged by a cylindrical pin 40 rising from the upper end of an 90 eccentric shaft 41 whereby the said eccentric shaft 41 will be maintained in its proper position relative to the piston. In the under face of the piston head or cap 37 is formed or secured a race-way 42 to receive balls or 95 anti-friction devices 43 carried by a ball-retainer 44 and resting upon a lower raceway 45 which is supported by a shoulder 46 at the upper end of the eccentric shaft 41. The lower end of the said eccentric shaft is 100 provided with a trunnion 47 which passes centrally through the lower head or cap 48 of the piston and has its lower extremity fitted angularly in the lower cylinder head 49 and in a bracket or block 50 disposed 105 against the under side of the said head 49 and having a central boss 51 which fits within the said head. The central angular opening of the bracket 50 also receives an angular boss 52 on the upper side of a plate 53 110 which is adjustably secured to the said bracket 50 by screws 54, as will be readily understood on reference to Fig. 2. A small axial passage 55 is formed through the trunnion 47 and the boss 52 so that the lubricant which is fed to the boss through a tube 56 may pass upwardly through said trunnion and the eccentric shaft to the interior 115 of the piston and lubricate the working parts. It will be readily noted that the said passage 55 does not extend through the entire length of the eccentric shaft, as such construction would be unnecessarily laborious and expensive. The passage is, however, diverted to the side of the eccentric 120 shaft and leads into a by-pass tube 57 extending parallel with the shaft within the piston and having its upper end in communication with a similar passage 58 formed in the upper portion of the eccentric shaft. 125 130

This upper passage 58 communicates with the passage 38 in the shaft 34 and also has lateral branches, indicated at 59 and 60, so that the lubricant may be conveyed to 5 the anti-friction bearings 43 and also to the interior of the piston. A branch 61 leads from the passage 55 for a similar purpose.

The tube 56 supplies the lubricant to the lower end of the eccentric shaft, as before 10 stated and as will be readily understood upon reference to Fig. 2 of the drawings, and this tube is composed of a series of sections connected by couplings 62 so that the tube may be of a length necessary to extend to and beyond the mouth of the well where it is connected with a container 63 in which is a screw-operated plunger 64. It is to be understood that heavy or thick lubricant is to be employed and it will be fed 20 into the interior of the piston through the tube 56 and the several passages, above described, so that it will be forced to the working parts and reach all surfaces which would be otherwise subjected to excessive wear.

25 A reducing cap 65, which is similar in all respects to the cap 24, is secured against the lower head 49 and to the lower end of the cylinder 25 by bolts 66 in the same manner as the bolts 26 secure the cap 24 and the 30 head 28 to the cylinder. To the lower end of the cap 65 is secured the inlet tube 67 which is preferably in the form of a cylindrical screen having its lower end closed by an imperforate cap 68. The imperforate 35 cap 68 will prevent the entrance of sand and gravel and other foreign matter through the lower end of the inlet tube and the screen-like construction of the said inlet tube will prevent the entrance of any large substances 40 into the working mechanism of the pump. By making the screen of a sufficient degree of fineness, it will be obvious that the water passing into the pump will be practically free of sand or other matter which would 45 tend to wear away the working parts, so that the pump will prove exceedingly durable. To the upper end of the inlet tube 67, I secure a plurality of leaf-springs 69 which are bowed outwardly so as to bear against 50 the side of the well or of the casing therein and thereby hold the pump against oscillation as it is being lowered into or removed from the well, so that the liability of damage to the well or the casing will be minimized. The lower ends of the springs 69 55 play freely in loops 70 provided on the inlet tube near the lower end thereof so that the springs may expand more or less and, consequently, accommodate themselves to 60 the diameter of the well and maintain the pump in a central vertical position within the well after it is lowered. It is to be understood that the pump is intended to be submerged in the water in the well so that

the supply of water will be constant when 65 the pump is in operation.

The piston caps or heads 37 and 48 are connected by a cylindrical piston body 71, the caps being secured to the opposite ends of the piston body by screws or studs 72 70 inserted through the heads or caps into the ends of the body, as clearly shown in Fig. 2. The piston is provided with a plurality of longitudinal radial slots 73 in which blades 74 are mounted, the said blades being projected and retracted as the piston rotates so as to produce a suction through the pump which will have the effect of drawing water into the cylinder through the lower end thereof and subsequently 80 forcing the water from the cylinder through the upper end of the same. The blades 74 are carried by radial arms 75 mounted slidably in bushings 76 in the piston body near the upper and lower ends of the same. 85 The inner ends of the arms 75 are reduced, as shown at 77, to fit between upper and lower ring segments 78 to which they are pivotally attached by pins or rivets 79, as will be readily understood. These ring segments 90 95 100 105 110 115 120 segments 78 are mounted between retaining rings 80 which are fitted loosely around the eccentric shaft 41 and are provided on their opposed faces with peripheral flanges 81, the space between the said flanges and the eccentric shaft forming a guiding chamber for the ring segments, as will be readily understood. The ring segments and the retaining rings are duplicated near the upper and lower ends of the eccentric shaft and the upper retainers are held against dropping by a supporting ring 82 which is fixed upon the shaft below the lower ring of the upper pair of retaining rings and immediately above the lateral passage 59 for the lubricant. The lower retainer rings are supported upon a washer or supporting ring 83 which is in turn supported by the lower piston head 48, and a second supporting ring 84 is fitted upon the eccentric shaft above the lower retaining rings and immediately below the lateral passage 61 for the lubricant. The ring segments 78 are of such radial dimension as to fit against the eccentric shaft and also against the peripheral flange of the adjacent retaining ring, but circumferentially they are of such dimensions that they will be spaced apart when in position. They thus provide for free independent pivotal movement of the radial blade-supporting arms so that the blades will be projected and retracted as the piston rotates around the eccentric shaft.

The head 49 is provided with a segmental slot 85 similar to the slot 29 in the upper 125 head 28 and this slot 85 constitutes the water inlet for the cylinder. The slots 29 and 85 are disposed at opposite sides of a

- vertical rib or abutment 86 formed within the cylinder 25 and extend in opposite directions therefrom, the said abutment, consequently, serving to prevent the water passing directly from the inlet to the outlet. A wear-plate 87 is disposed against the abutment 86 and is secured in place by set-screws 88 threaded in the wall of the cylinder and having their inner ends fitted in the said wear-plate so that by turning the set-screws the wear-plate may be adjusted to or from the piston and thereby prevent slippage of the water without binding upon the piston and also providing a simple means for adjusting the parts to compensate for wear of the piston or the abutment. The oil tube 56 passes through the cylinder immediately adjacent this wear-plate 87 and a concave groove 88' is preferably provided in one side of the wear-plate to accommodate the said oil tube, an opening 56' being provided in the head 49 to accommodate the lower portion of the tube and the upper portion of the tube passing through the slot 29. At a point diametrically opposite the abutment 86, the cylinder is formed with a segmental enlargement or projection, indicated at 89, and to the inner face of this projection or enlargement is fitted a wear-plate 90, the said wear-plate being secured within the cylinder by screws or bolts 91 inserted through the ends of the plate into the walls of the cylinder and the intermediate portion of the wear-plate being adjustable inwardly by set-screws 92 fitted in the wall of the cylinder and bearing against the outer face of the wear-plate, as shown in Fig. 4. It will be readily understood that by turning the set-screws 92 inwardly the intermediate portion of the wear-plate will be driven somewhat nearer the piston so that the blades 74 may work close enough to the wear-plate to produce the proper suction through the pump cylinder and prevent slippage of the water without creating a retarding friction between the parts. The slots 29 and 85 extend from the opposite sides of the abutment 86 to the ends of the projection or enlargement 89.
- In operation, the driving shaft is rotated through the medium of the power applied directly to the upper solid end section thereof, and, as the lower end of the driving shaft is rigid with the upper piston head 37 and both piston heads are firmly secured to the piston body by the screws inserted thereinto, it will be seen at once that the rotation of the driving shaft causes the piston to rotate between the cylinder heads 28 and 49 and within the cylinder body. As the blades 74 and the blade-carrying arms 75 are mounted in the piston, they will necessarily follow the movement of the same, and, as the inner ends of the blade-carrying arms are connect-

ed to the ring segments held against the eccentric shaft by the retainers, it is obvious that the rotation of the piston will cause the blades to be projected as they approach the enlargement 89 of the cylinder and, consequently, a partial vacuum will be created in the rear of the blade which happens to be projected to the wear-plate 90 and between the said blade and the abutment 86 so that water will be drawn through the inlet opening 85 into the cylinder. The blades will be successively projected as they approach the wear-plate 90 and, consequently, will successively take in the water and force the same around to the opposite side of the enlargement or projection 89, after which the water will escape through the upper segmental slot 29, it being understood that as the blades force the water toward the slot 29 there will be a tendency to compress the water, which will be relieved only by the escape of the water through the said slot, inasmuch as the abutment 86 will prevent the water merely traveling in a circular path around the piston.

It will be readily understood from the foregoing description, taken in connection with the accompanying drawings, that I have provided a very compact and easily operated pump by the use of which a steady flow of water may be obtained at the mouth of a deep well, so that a field may be irrigated or the water otherwise used at all times when needed. It will be readily noted that there is no carrying strain upon the piston and, consequently, the piston may rotate easily and with the application of slight power. The driving shaft is supported from its upper end by the adjustable collar or block 12 resting in the upper bearing plate 9, and, as the said bearing plate is free to move annularly upon the anti-friction devices 8, motion may be imparted to the shaft very readily and quickly. The supporting screws or threaded studs 6 may be adjusted so that the weight of the driving shaft will be entirely removed from the piston, and, should the said screws be adjusted unequally so that the supporting plate 5' would be given an inclination, the shaft would still maintain its vertical position owing to the fact that the collar or block 12 may move about its seat in the upper bearing plate 9. By adjusting the screws 54 at the lower end of the cylinder, the eccentric shaft may be raised or lowered, inasmuch as the lower extremity of this shaft rests upon the boss on the plate 53, and, as the raising or lowering of the eccentric shaft will raise or lower the piston, it will be readily seen that the weight of the piston is taken off the lower cylinder head 49 and wear between those parts is obviated. The entire weight of the piston is carried by the anti-friction devices 43 which

are supported by the upper end of the eccentric shaft so that the piston may be rotated easily and at a high speed without requiring any uneconomical operation of the motor.

5 It will be readily noted that the interior of the piston is hollow to accommodate the ring segments and the retaining rings therefor and through which the eccentric shaft is caused to project and retract the blades and 10 means are provided to distribute lubricant to all the moving parts, and this lubricant will also serve to prevent the entrance of fine sand or other abrading material to the moving surfaces.

15 The several parts of the device are very compactly arranged and repairs may be easily made when necessary.

What I claim is:—

1. A rotary pump comprising a cylinder, 20 heads forming closures for the upper and lower ends of said cylinder and provided with outlet and inlet openings respectively, an abutment within the cylinder extending between said heads and disposed between said heads and around said eccentric shaft, blades mounted radially in the said piston, and 25 means connected with said blades and engaging the eccentric shaft for projecting the blades as they move from the abutment and retracting the same as they move toward the abutment.

35 2. A rotary pump comprising a cylinder, a hollow piston mounted therein, means for rotating the piston, an abutment extending longitudinally of the cylinder at one side thereof, a projection at the opposite side of 40 the cylinder, blades carried by the piston, and means comprising a stationary member supporting the piston and housed by and within the same for moving the blades outward as they approach the projection and 45 moving them inwardly as they approach the abutment.

3. A rotary pump comprising a cylinder having upper and lower heads, an internal longitudinal abutment extending between 50 the heads, a hollow piston mounted between said heads, means for rotating the piston, blades carried by the said piston, means housed within the piston to project and retract the said blades, and lubricant conveyer 55 extending through the cylinder adjacent the abutment and communicating through the lower end of the cylinder with the interior of the piston.

4. In a rotary pump, the combination of 60 a cylinder having upper and lower heads, a driving shaft journaled in the upper head of the cylinder and extending below the same, a hollow piston rigid with the lower end of said driving shaft and extending be- 65 tween the heads of the cylinder, means for

rotating the said driving shaft, blades carried by the piston, a support for the piston seated in the lower head of the cylinder and extending to the upper end of the piston, and means within the piston carried by said 70 support to project and retract the blades.

5. In a rotary pump, the combination of a cylinder having upper and lower heads, a hollow piston fitted between said heads, a driving shaft extending through the upper 75 head and rigid with the piston, a stationary eccentric shaft supported in the lower head of the cylinder and extending within the piston to support the same, blades mounted in the piston, and supports for the said 80 blades slidable radially in the piston and movable around the eccentric shaft whereby the blades will be projected and retracted.

6. In a rotary pump, the combination of a cylinder having upper and lower heads, a hollow piston fitted between the said heads, a driving shaft extending through the upper head and rigid with the piston, a support for the piston carried by the lower head of the cylinder, and an anti-friction bearing interposed between the upper end of said support and the upper end of the piston. 85

7. In a rotary pump, the combination of a cylinder having upper and lower heads, a hollow piston fitted between the said heads, 90 means for rotating the piston, an eccentric shaft carried by the lower head of the cylinder and disposed within the piston, blades mounted in the piston and extending longitudinally thereof, blade-carrying arms slidable radially in the piston, retaining rings fitted around the eccentric shaft, and ring segments within said retaining rings pivoted to the inner ends of the blade-carrying 100 arms. 105

8. In a rotary drum, the combination of a cylinder having upper and lower heads, a hollow piston between said heads, means for rotating the piston, an eccentric shaft held stationary within the piston, supporting 110 rings fixed upon the said eccentric shaft, retaining rings mounted on said supporting rings around the eccentric shaft, ring segments held to the eccentric shaft by the retaining rings, blade-supporting arms slidable radially in the piston and having their inner ends pivoted to the ring segments, and blades carried by the outer ends of the said arms. 115

9. In a rotary pump, the combination of a cylinder having upper and lower heads, a hollow piston between said heads, an eccentric shaft held stationary within the hollow piston, retaining rings fitted around said shaft and having peripheral flanges on 120 their opposed faces, ring segments seated within said rings between said flanges and the eccentric shaft, blade-supporting arms slidable radially in the piston and having their inner ends fitted between and pivoted 125 130

to said ring segments, and blades carried by the outer ends of said arms.

10. In a rotary pump, the combination of a cylinder having upper and lower heads, a hollow piston between the said heads, a driving shaft for the piston extending through the upper head of the cylinder and rigid with the upper end of the piston, an eccentric shaft disposed within the piston and having its lower end fitted in the lower head of the cylinder and its upper end provided with a stud fitting in the lower end of the driving shaft, blades carried by the piston, blade-supporting arms slidable radially in the piston, and means controlled by the eccentric shaft and acting on said arms to project and retract the blades.
11. In a rotary pump, the combination of a cylinder having upper and lower heads, a

hollow piston between the heads, means for 20 rotating said piston, an eccentric shaft disposed within the piston and having its upper end adapted to support the piston, a trunnion extending from the lower end of the said shaft through the lower end of the 25 piston and the lower head of the cylinder, a bracket on the under side of the head having an angular engagement with said trunnion, and a supporting plate adjustably secured to the said bracket and having a boss 30 fitting within the bracket and supporting the lower end of the eccentric shaft.

In testimony whereof I affix my signature in presence of two witnesses.
